CONTAINER FOR A MESSAGE TRANSMITTER AND CIGARETTES

June Wood, Scottsdale, Ariz., assignor to Aero
Electronics Development Co., Inc., Tempe, Ariz.

Filed June 21, 1971, Ser. No. 155,385

Term of patent 14 years

Int. Cl. D27—06

U.S. Cl. D85—2 B

Fig. 1

Fig. 2

Fig. 4

Fig. 3

FIG. 1 is a front perspective view of a container for a message transmitter and cigarettes, showing my new design;

FIG. 2 is a rear elevational view;

FIG. 3 is a bottom plan view; and

FIG. 4 is a side elevational view thereof.

I claim:

The ornamental design for a container for a message transmitter and cigarettes, as shown.
